[57] CLAIM

The ornamental design for a telephone booth, substantially as shown and described.

DESCRIPTION

FIG. 1 is a front perspective view of a telephone booth showing my new design, the rear being unornamented; FIG. 2 is a side view taken from the right of FIG. 1; FIG. 3 is a side view taken from the left of FIG. 1; FIG. 4 is a top view thereof, the bottom being a mirror image;

FIG. 5 is a transverse section taken in the direction of the arrows on line 5—5 of FIG. 1;

FIG. 6 is a vertical section taken in the direction of the arrows on line 6—6 of FIG. 1.

The broken line showing of the telephone equipment and slot in FIGS. 1, 2, and 5 is for illustrative purposes only.

Fig. 2.
